METHOD AND MEANS FOR STARTING
DIESEL ENGINES

Okiye Yamashita, Tokyo, Japan

Application June 6, 1939, Serial No. 277,714

2 Claims. (Cl. 123—179)

My invention relates to a method of starting four-cycle multi-cylinder Diesel engines and more particularly to a Diesel engine of abnormally low compression ratio having special change-over valve gear for starting the engine by this method, and its object is to easily start such engines with comparatively low compression ratio developing higher power by super-charging.

It is well known in the art that if the suction air for Diesel engines is increased by super-charging the output of the engine can be increased, but the explosion pressure might be raised excessively high. Accordingly if in a Diesel engine designed for ordinary compression ratio, that is, 14 to 18 the compression ratio might be reduced below 14, e. g. 8 to 12, the maximum explosion pressure can be sufficiently reduced. In other words, if a Diesel engine of comparatively low compression ratio is supercharged the output can be increased maintaining the maximum pressure at a moderate extent. If, however, an ordinary centrifugal blower is used as a super-charger for the engine the initial pressure is too low to start the engine when the revolution of the blower is slow. Thus a special method should be taken for starting a Diesel engine of low compression ratio which can not be started by an usual manner.

This invention is to provide a new method for the above purpose, and I have provided a valve for the super-charger of a four-cycle multi-cylinder Diesel engine to interrupt the air supply to the engine in case of its starting and change-over valve and cam devices for operating some of the cylinders, for example, four cylinders among nine, as air compressors in such manner that air is sucked from the exhaust valve into the cylinder and the compressed air is delivered to the suction manifold through the suction valve of the same cylinder so that the compressed air may be supplied to the remaining cylinders through their suction valves to operate the engine according to the normal four cycles. Then the compression is effected once for each revolution in the compressor cylinders while the remaining five cylinders will operate as a four-cycle Diesel engine sucking air into each cylinder from the suction manifold once for two revolutions so that the five cylinders may be supplied with air twice of four cylinder volumes, viz. 5 cylinder charges corresponding to the super-charge of 1.6 times

$$\left(\frac{4 \times 2}{5} = 1.6 \right)$$

and thus the higher compression pressure is obtained to start the engine easily.

My invention will be better understood from the following description when considered in

connection with the accompanying drawings, and its scope will be pointed out in the appended claims.

In the accompanying drawings Fig. 1 is a sectional view taken for explanation of the principle of operation of my invention; Fig. 2 is a sectional elevation of a cylinder of Diesel engine having a valve gear used in carrying into effect my invention; Fig. 3 is a sectional side view thereof; Fig. 4 is a front view of a modified form of the valve gear used in carrying into effect my invention as applied to a radially arranged nine cylinder engine; Fig. 5 is a partial sectional view thereof; and Fig. 6 is a perspective view showing a modified form of change-over valve gear embodying my invention.

Referring to Fig. 1 of the accompanying drawings, A₁, A₂, . . . represent engine cylinders working on a normal four cycle operation and B₁, B₂, . . . are cylinders which can be converted into compressor cylinders when starting the engine. E represents exhaust valves; S are suction valves; I and I' designate exhaust manifolds connected to the cylinders A₁, A₂, . . . and B₁, B₂, . . . respectively through the exhaust ports 2 and 2'. 3 represents a suction manifold leading to the suction valves of each cylinder through the branched suction passages 4. 5 represents a super-charger connected to the suction manifold 3 and having a rotor 6. 7 is a control valve provided in the suction passage 8 of the super-charger 5. Assume the cylinders B₁, B₂, . . . to be provided with change-over valve gears to operate these cylinders as the compressors when the engine is started by means of external power or some other prime mover such as an electric motor. In other words, the exhaust valves E of the cylinders B₁ and B₂ are used as the inlet valves and the suction valves S of these cylinders are used as the delivery valves when the valve operating devices are changed-over. Then the cylinders B₁, B₂, . . . will be operated as the compressors by sucking air through the exhaust valve E and delivering the compressed air through the suction valve S and the suction passages 4 into the suction manifold 3 so that the compressed air may be supplied to the cylinders A₁, A₂, . . . when the suction valve S of such cylinders is opened. Thus the cylinders A₁, A₂, . . . are operated according to the normal four cycles to develop driving power by themselves. When the engine speed arrives at a certain high speed the cylinders B₁, B₂, . . . are converted to normal engine cylinders by means of special change-over valve gears, then the cylinders B₁, B₂, . . . can be self-started by being driven by the other cylinders, thus the starting operation is completed.

Now take a six-cylinder Diesel engine having cylinders in line and provided with a super-

charger and assume three cylinders out of six to be operated as air compressors temporarily driven by external power. Then three cylinders B₁, B₂ and B₃ will be operated as air compressors by sucking air from the exhaust valves and delivering through suction valves the compressed air into the suction manifold leading to the remaining three cylinders A₁, A₂ and A₃ as the combustion air so that

$$\frac{3 \times 2}{3} = 2$$

viz, twice the normal volume of air is supplied into the cylinders A₁, A₂ and A₃ and the engine can be easily started. The engine is driven in the above manner until it arrives at a certain high speed and the super-charger can produce sufficiently high pressure, then the valve for the super-charger is opened and also the change-over cams for the cylinders B₁, B₂ and B₃ are restored to the original positions and fuel is supplied to these cylinders, then the cylinders will be easily self-started as a Diesel engine.

In Figs. 2 and 3, I have shown a change-over valve device for effecting the above described principle of operation of my invention. B₁ is a cylinder to be converted to a compressor. 10 represents a piston; 11 a piston rod; 12 a crank shaft; and 13 the cam shaft. 14 and 15 represent valve operating rods for exhaust valves and suction valves respectively. 16 and 17 are hinged levers acting on the valve stem 18 biased by a spring 19. The cam shaft 13 is arranged to be shifted axially and has formed thereon special cams 20, 21 and 22, 23 for the cylinder B₁ to cooperate with the valve operating rods 14 and 15 respectively for converting the cylinders from the normal four cycle operation to compressor operation, and also cams 24 and 25 for the cylinder A₁ to cooperate with the valve operating rods 14 and 15 respectively. The cams 24 and 25 have sufficient breadth to always act on the respective rods 14 and 15 independently of the axial shifting of the cam shaft 13. In such arrangement the cylinder B₁ can be converted to compressor operation by shifting the cam shaft 13 axially to the left in Fig. 3, then the cams 22 and 23 are used instead of the cams 20 and 21, while the cams 24 and 25 remain in operation.

In Figs. 4 and 5 I have shown another form of change-over valve device applied to a nine-cylinder Diesel engine of radial arrangement. A₁, A₂, A₃, . . . A₅ represent cylinders capable only of normal operation. B₁, . . . B₄ are cylinders to be converted as air compressors having change-over valve gears. 14 is a rod for operating the exhaust valve and cooperating with a cam ring 26, on which are formed four cams 27 on the same circumference and another group of eight cams 28 for the compressor operations on the adjacent circumference. 15 is a rod for operating a suction valve and cooperating with the cam ring 29, on which are formed four cams 30 on the same circumference and another group of eight cams 31 on the adjacent circumference. 32 represents a gear on the engine crank shaft. The cam rings 26 and 29 are made integral, but shown as having different diameters in Fig. 4 for the sake of clearness, but they may have the same diameter as shown in Fig. 5. The cam rings are driven in a direction opposite to the crank shaft by means of gearings 32, 33 and 34 and at a speed of revolutions of one-eighth of that of the crank shaft. The cam ring is also mounted on the bearing 36

(Fig. 5) to be shifted axially by means of a strap 37.

The operation of the valve gears shown in Figs. 4 and 5 is as follows: In the normal four cycle operations the cams 27 and 30 cooperate with the rods 14 and 15 for exhaust and suction valves respectively of the cylinders B₁, . . . B₄. But when starting the cam rings 26 and 29 are shifted axially, then the cams 28 and 31 cooperate with 10 the valve operating rods 14 and 15 respectively. Accordingly the cylinders B₁, B₂, . . . B₄ are operated as air compressors sucking air into the cylinder through the exhaust valves and delivering the compressed air through the suction valves into 15 the suction manifold repeating twice operations in one revolution of the crank shaft.

The same object of changing the valve operations can be attained by an arrangement of valve gears without shifting the cam shaft or cam ring 20 as in Figs. 3 and 5. One of such valve gears is shown in Fig. 6, wherein 38 represents a cam ring provided with cam surfaces 39 and 40 cooperating with the cam rollers 41 and 42 respectively. The rollers 41 and 42 are mounted on one end of 25 the parallel rods 43 and 44 respectively, the other end of these rods being connected to a sector arm 45. 46 represents springs. To the arm 45 is joined a swinging rod 47 which is hinged to the valve operating rod 48 at 49. The arm 45 is curved along a circular arc having the radius 30 equal to the length of the swinging rod 47. 50 represents a part of the shifting rod and 51 is a hinged lever acting on the valve spindle 52. If the rod 47 is shifted along the sector arm 45 to the left end in Fig. 6 the valve will be operated by the cams 40, while if it is shifted to the right end the valve will be controlled by the cams 39. Suppose now the cam 40 operates the valves for 35 compressor operation and the cam 39 effects the 40 valve action for ordinary four cycle Diesel engine, then if the rod 47 is moved from the left end position to the right the operation of the cylinders can be changed from air compressor to ordinary Diesel engine.

Though I have described in the foregoing a few examples embodying my invention, yet it will be understood that any desired number of cylinders out of a group of cylinders may be operated as air compressors at starting by the above described manner to supply compressed air as the suction air into the other cylinders, thereby giving high initial pressure even at a low speed running so as to facilitate the starting of the engine.

According to this invention, the super-charger of a four-cycle multi-cylinder Diesel engine may be of an ordinary centrifugal blower instead of a displacer type super-charger such as Roots blower or eccentric disc type blowers even if the compression ratio of the engine is low. By the 55 present method the engine may be started with 60 less torque than that necessary when all cylinders are started at the same time.

For engines designed for the compression ratio of 12 to 14, the super-charger is not necessary 65 for converting the cylinders operated as air compressors at first into engine operation, but the object can be satisfactorily attained by merely bringing the engine speed up to a certain high speed. Accordingly this invention can be applied to the starting of four cycle multi-cylinder Diesel engine without super-charger if the compression ratio is not exceedingly low.

I claim:

1. A Diesel engine for operation at abnormally low compression ratio comprising a super-

charger, a valve controlling the passage of air to said super-charger, engine cylinders having exhaust and suction valves, separate connections between said super-charger and the suction valves, a change-over gear for adjusting the valves of certain of the engine cylinders for converting the latter into compressor cylinders to cause air to be drawn through the exhaust valves of the compressor cylinders and to be delivered through the suction valves thereof to the remaining engine cylinders, thereby supercharging the said remaining cylinders to facilitate self-starting.

2. A method of starting four-cycle multiple cylinder Diesel engines having an abnormally low compression ratio such as 8 to 12 and a rotary blower as a super-charger and exhaust and suction valves and a change-over gear for said valves, consisting in closing the valve of the super-

charger, driving the engine by external power, converting a suitable number of the engine cylinders into air compressors temporarily at the starting by adjusting said change-over gear to cause air to be drawn through the exhaust valves of the compressor cylinders and to be delivered through the suction valves thereof to the suction manifold of the remaining engine cylinders, thereby super-charging the latter cylinders 5 to facilitate self-starting as Diesel engine cylinders, interrupting the external drive, and restoring the valve gears to normal working condition to change the compressor cylinders over for operation as normal engine cylinders opening the valve of the super-charger so that said compressor cylinders may be started in operation as Diesel engine cylinders by the power applied thereto by the formally started engine cylinders. 10 15
